Primary Examiner — Ania Aman(74) *Attorney, Agent, or Firm* — K&L Gates LLP(57) **CLAIM**

The ornamental design for a coolant apparatus as shown and described.

DESCRIPTION

FIG. 1 is a left side view of a coolant apparatus, according to the present invention.

FIG. 2 is a rear view of the coolant apparatus of FIG. 1.

FIG. 3 is a right side view of the coolant apparatus of FIG. 1.

FIG. 4 is a front view of the coolant apparatus of FIG. 1.

FIG. 5 is a top view of the coolant apparatus of FIG. 1.

FIG. 6 is a bottom view of the coolant apparatus of FIG. 1; and,

FIG. 7 is a front-top-left perspective view of the coolant apparatus of FIG. 1.

The broken lines in FIGS. 1-7 illustrate portions of the coolant apparatus that form no part of the claimed design.

1 Claim, 7 Drawing Sheets(56)
